SOLDER GUN

Alfred W. Madl, Milwaukee, Wis., assignor to John Oster
Manufacturing Co., Milwaukee, Wis., a corporation of
Wisconsin

Filed June 28, 1961, Ser. No. 65,741

Term of patent 14 years

(Cl. D26—1)

FIG. 1 is a perspective view of a solder gun, showing my new design;

FIG. 2 is a top view;

FIG. 3 is a side elevation view taken from the side of the solder gun opposite to that shown in FIG. 1;

FIG. 4 is a front view; and

FIG. 5 is a rear view thereof.

The dominant features of my design reside in the portions shown in full lines, and are characterized by the main body portion of the housing having a rhomboid shape when viewed from the side and opposite sides of the front and rear of the main body portion being stepped to have a reduced thickness.

I claim:

The ornamental design for a solder gun, as shown and described.
